UNITED STATES PATENT OFFICE.

JOHN J. CARTER AND ARTHUR MILTNER, OF ANDERSON, INDIANA, ASSIGNEES TO
GENERAL MOTORS CORPORATION, OF ANDERSON, INDIANA, A CORPORATION OF
DELAWARE.

TENSIONING DEVICE.

Application filed April 7, 1923. Serial No. 630,609.

To all whom it may concern:

Be it known that we, JOHN J. CARTER and ARTHUR MILTNER, citizens of the United States of America, residing at Anderson, county of Madison, State of Indiana, have invented certain new and useful Improvements in Tensioning Devices, of which the following is a full, clear, and exact description.

10 This invention relates to winding machines for electrical apparatus, and particularly to machines for winding armatures of the drum wound type, wherein wire is supplied to a cylindrical core having winding slots which extend substantially or nearly parallel to the axis of the core.

One object of this invention is to provide apparatus for maintaining the wire, which is unwound by means of a winding machine 20 of the type referred to, under substantially constant tension while there may be variations in the linear unwinding speed of the wire.

Further objects and advantages of the 25 present invention will be apparent from the following description, reference being had to the accompanying drawings, wherein a preferred embodiment of one form of the invention is clearly shown.

30 Fig. 1 is a plan view of a tensioning device constructed in accordance with the present invention, and a winding machine with which it operates;

Fig. 2 is an end view of the tensioning device, some of the parts being shown in section for the sake of clearness;

Figs. 3 and 4 taken together show a side view of the tensioning device;

Fig. 5 is a sectional view taken on the line 40 5—5 of Fig. 4.

The invention includes generally means for supporting a supply reel of wire, means for applying tension to the wire as it is being unwound from the supply reel by means of a winding machine of the type referred to, said tensioning means including provisions for maintaining substantially constant tension in the wire although the linear unwinding speed of the wire may vary.

Supply reel holder.

A post 30 is attached to base 31 and supports bearings 32 and 33 lubricated by means of an oiler 34. On these bearings is mounted a spindle 35 one end of which

supports a reel of wire 36 indicated by dot and dash lines. Tapered sleeve 37 fits on spindle 35 and is adapted to clamp the core of reel 36, which is generally of wood against a plate 39, when the nut 38 is 60 screwed along the spindle 35.

Tensioning device.

Plate 39 is secured to spindle 35 by means of key 40 and is provided with brake drum 65 41.

A supporting bracket 45 is attached to post 30 by means of screws 46, and a brake shoe 47 is pivotally mounted on bracket 45 by means of screw 48. A brake lining 49 70 adapted to engage with brake drum 41 is attached to brake shoe 47 by means of rivets 50. Brake shoe 47 is provided with a boss 52 which contacts with a plunger 53.

Guiding brackets 55 and 56 are attached 75 to post 30 by means of screws 57 and pins 58. The upper end of rod 60 is reduced to fit within the plunger 53 which passes through guiding bracket 55 and engages with boss 52. The central portion of rod 80 60 is threaded as shown at 61 to receive adjusting nuts 62 and 63, and the lower end of said rod 60 passes through guiding bracket 56 and is provided with a flat portion 64. Coil springs 65 and 66 surround 85 rod 60 and are located between the plunger 53 and adjusting nuts 62 and between adjusting nuts 63 and bracket 56 respectively. Spring 65 urges rod 60 upwardly and 66 urges plunger 53 upwardly, so that the 90 brake is applied through the combined action of both springs.

Boss 70 on post 30 is provided with holes 71 on the opposite ends thereof either of which will receive a bolt 72 carrying a 95 washer 73 which provides a pivotal mounting for lever 74. The provision of two holes 71 renders post 30 adaptable for either right or left hand mounting of the brake shoe described heretofore. The portion 64 of rod 100 carries pin 75 which cooperates with the forked end of lever 74. The opposite end of lever 73 is provided with holes 76 to receive end of rod 77 and to permit of adjustment by providing different points of attachment for rod 77.

Pipe 80 is screwed into flange 81 which is bolted to base 31 by means of bolts 82. A bifurcated bracket 83 is reduced at its stem portion 84 to fit within pipe 80, and is se- 110

cured thereto by means of pin 85. Branches 87 and 88 of bracket 83 support a rod 89, secured by pins 90, which provides pivot lever arms 95 and 96. The ends of these 5 lever arms 95 and 96 nearest the real supports are apertured to receive S-shaped hooks 97 and 98, respectively. The opposite ends of the hooks 97 and 98 are connected with the upper ends of rods 99 and 100, 10 which extend into cylinders 105 and 106 respectively. Each rod is provided with a plunger 107 engaged by coil spring 108. Upward movement of plungers 107 are limited by means of pins 109 attached thereto 15 and operating in slots 110 formed in the side walls of the cylinder 105 and 106 respectively.

The construction of parts enclosed by cylinder 106 is exactly the same as those 20 within cylinder 105. Rods 77 and 78 are attached to the lower ends of the cylinders 105 and 106 respectively. The attachment of rod 77 to lever 74 has been described. Rod 78 is attached to a lever 74^a pivoted on 25 frame 30^a and actuates parts identical with those actuated by lever 77. The parts on frame 30^a which correspond to parts on frame 30 are designated by the same reference number followed by the reference 30 letter "a."

At the opposite ends of the lever arms 95 and 96 are mounted guiding wheels 115 and 116 respectively, provided with grooves 117 and 118 respectively. Guard members 119 35 and 120 for the guiding wheels 115 and 116 are attached to the lever arms 95 and 96 by means of screws 121 and 122.

Operation of tensioning device.

40 The tensioning device described is adapted to be used with a winding machine of the type disclosed in the copending application of Carter and Miltner, Serial No. 630,610, filed April 7, 1923. This machine comprises a base 130, to which base 31 is attached by bolts 131, and a table 132 supporting electric motor 133 which drives a rotating head 134 mounted on shaft 135 through gearing not shown. Armature 136 is 45 mounted between head 134 and block 137 resiliently urged toward head 134 and mounted on support 138. During winding operation, armature 136 is rotated at right angles to the axis of its shaft. The armature 136 is provided with a cylindrical core having winding slots extending substantially parallel to the axis of the core. Head 134 is located a substantial distance below the wheels 115 and 116, and is obliquely 50 disposed relative to the planes of these wheels. The surface of the head is constructed so as to guide the wires into the armature core slots.

The winding of wire upon an armature 55 of the above type can be compared to wind-

ing upon an oblong block during which the linear speed of the winding of the wire will accelerate and decelerate intermittently. Therefore, in order to maintain the tension of the wire substantially constant at all 70 times, the present invention may be used advantageously.

Wires 140 and 141 are led off the supply reels 36 and 36^a and are passed through grooves 117 and 118 in guiding wheels 115 75 and 116 and are attached in any convenient manner to the armature 136. Rotation of head 134 and armature 136, will pull the wires 140 and 141 causing reels 36 and 36^a to rotate. As the linear speed of the winding of wires 140 and 141 rapidly accelerates, there will be a downward jerk exerted on guiding wheels 115 and 116, thus swinging the lever arms 95 and 96 on rod 89 and causing the hooks 97 and 98 to move upwardly. This jerk is the result of the inertia drag exerted by the heavy supply 80 reels.

When one of the arms, such as arm 96, is jerked downwardly the distance along 90 the wire from the supply reel 36 to the winding machine is shortened thereby partly compensating for sudden acceleration in winding speed. At the same time this arm movement is used to release the brake pressure on drum 41 so that when the supply reel 36 is accelerated there will be a substantial decrease in friction drag to offset the inertia drag due to suddenly accelerating 95 the heavy supply reel. The release of brake pressure is accomplished in the following manner:

The upward movement of hook 98 will 100 actuate plunger 107 to compress spring 108 while causing the rod 78 to move upwardly. Lever 74 will rotate counterclockwise causing rod 60 to move downwardly against the action of spring 65, thereby releasing tension of spring 66 against plunger 53. This will cause the pressure exerted by brake 105 shoe 47 on brake surface 41 to be reduced and allow the supply reel of wire 36 to run with less friction drag to compensate for the increase in drag due to overcoming inertia of the reel and spindle whenever there 110 is an acceleration of the linear winding speed of the wire.

When the linear winding speed of the wires 140 and 141 decelerates, the downward pull on guiding wheels 115 and 116 and the tension on springs 108 will be relieved. Consequently the springs 65 and 65^a will be permitted to exert pressure upwardly through springs 66 and 66^a to apply full brake pressure to the brake drums.

The downward movement of rods 61 does 120 not relieve brake pressure entirely but this brake pressure is gradually reduced by gradually relieving compression in spring 66 while spring 65 is being further com- 125 pressed.

pressed by downward movement of rod 60. Downward movement of rod 60 is not effected jerkily in response to the jerking of arm 96, but is more gradually effected by 5 reason of the spring connection between the arm 96 and rod 60, namely, spring 108. The jerking movement of arm 96 causes spring 108 which is relatively long to be compressed, thus cushioning the jerking effect 10 and causing the rod 60 to move through a much shorter range of travel. Since the movement of rod 60 is short relative to the movement of arm 96, the spring 65 can be made relatively short and stiff because its 15 elongation and compression is limited to a small amount.

The interposition of spring 108 causes the spring 60 to be compressed more gradually than if the lever 96 were directly attached 20 to lever 74 and therefore the braking action is more gradually released and applied.

As a result of this construction there is less tendency for the tension in the wire to vary during the winding operation, hence 25 less liability of braking it. It is desirable to maintain substantially uniform tension in order that the wires will be closely and uniformly applied to the armature core.

The parts 105, 107, 108, 109 and 110 shown 30 in Fig. 4 constitute weighing scale for indicating the compression of spring 65. Pin 109 serves as a pointer to indicate divisions on a scale marked on the outside of barrel 105. The pointer is visible to the operator 35 of the winding machine so that it can be observed whether the tension on both wires is uniform.

By adjusting nuts 62 and 63 the compression of springs 65 and 66 can be varied to 40 change the brake pressure according to the size of wire or according to the diameter of the coil of wire on the supply reel. As the diameter of this coil decreases the brake pressure should be decreased. It is satisfactory to change the spring adjustment two 45 or three times as wire is unwound from a full supply reel to the core of the reel.

While the form of mechanism herein shown and described constitutes a preferred 50 form of embodiment of the invention, it is to be understood that other forms might be adopted, all coming within the scope of the claims which follow:

1. In a wire tensioning device, the combination with spindle and a brake drum connected therewith; of means for clamping a supply reel of wire to the spindle; a brake shoe; means for applying pressure to the shoe including a rod, a spring urging the 60 rod towards the shoe, a spring for transmitting pressure from the rod to the shoe; and means responsive to acceleration in unreeeling speed for moving said rod to compress the first spring and to relieve the second spring.

2. In a wire tensioning device, the combination with spindle and a brake drum connected therewith; of means for clamping a supply reel of wire to the spindle; a brake shoe; means for applying pressure to the 70 shoe including a rod, a spring urging the rod towards the shoe, a spring for transmitting pressure from the rod to the shoe; and means responsive to acceleration in unreeeling speed for moving said rod to compress the first spring and to relieve the second spring, said means including a pivoted arm and a wire guide wheel mounted thereon whereby the jerking of a wire passing around said wheel will rock the arm, and 75 means connecting the arm with the rod.

3. In a wire tensioning device, the combination with spindle and a brake drum connected therewith; of means for clamping a supply reel of wire to the spindle; a brake 80 shoe; means for supplying pressure to the shoe including a rod, a spring urging the rod towards the shoe, a spring for transmitting pressure from the rod to the shoe; and means responsive to acceleration in unreeeling 85 speed for moving said rod to compress the first spring and to relieve the second spring, said means including a movable member and a wire guide wheel mounted thereon whereby the jerking of a wire passing about said 90 wheel will move said member, and means connecting said member with the rod.

4. In a wire tensioning device, the combination with spindle and a brake drum connected therewith; of means for clamping a supply reel of wire to the spindle; a brake shoe; means for applying pressure to the shoe including a rod, a spring urging the 100 rod towards the shoe, a spring for transmitting pressure from the rod to the shoe; and means responsive to acceleration in unreeeling speed for moving said rod to compress the first spring and to relieve the second spring, said means including a movable member and a wire guide wheel mounted 105 thereon whereby jerking of the wire passing around said wheel will move the member, and a spring connection between said member and said rod.

5. In a wire tensioning device, the combination with spindle and a brake drum connected therewith; of means for clamping a supply reel of wire to the spindle; a brake shoe; means for applying pressure to the shoe including two springs one acting 115 through the other; means responsive to acceleration in unreeeling speed for compressing one spring whereby to relieve the second spring; and means for adjusting the initial compression of said springs.

6. In a wire tensioning device, the combination with a base; of a vertically extending post mounted on the base; a spindle rotatably supported by the post; means for securing a supply reel of wire to the spindle;

4
a brake drum connected with the spindle; a brake shoe mounted on the post and co-operating with the underside of the drum; a vertically extending rod mounted on said post; a spring urging the rod toward the shoe; a spring transmitting pressure from the rod to the brake shoe; a lever connected with the rod and pivotally mounted on the post; a lever pivotally supported above the spindle; a wire guide wheel on said lever; and means including a spring connecting said

levers whereby jerking the second lever will compress the first spring and relieve the second.

In testimony whereof we hereto affix our ¹⁵ signatures.

JOHN J. CARTER.
ARTHUR MILTNER.
